UNITED STATES PATENT OFFICE.

CHARLES LLOYD MACVEY, OF SHREVEPORT, LOUISIANA.

INTERNAL-COMBUSTION ENGINE.

1,369,827.

Specification of Letters Patent.

Patented Mar. 1, 1921.

Application filed September 26, 1919. Serial No. 326,528.

To all whom it may concern:

Be it known that I, CHARLES L. MACVEY, a citizen of the United States, residing at Shreveport, in the parish of Caddo and 5 State of Louisiana, have invented new and useful Improvements in Internal-Combustion Engines, of which the following is a specification.

My invention relates to improvements in 10 internal combustion engines of the rotary valve type.

An important object of the invention is to provide a simplified construction of rotary valve by use of which the four functions of intake, compression, firing and exhaust, may be performed upon one complete revolution of the valve.

A further object of the invention is to provide an internal combustion engine of 20 the above mentioned character having gravity operated means for lubricating the rotary valve, and for feeding the used oil from the valve to the interior of the cylinder for lubricating the piston, the spent 25 oil being subsequently exhausted from the cylinder.

A further object of the invention is to provide means whereby the rotary valve may expand longitudinally and circumferentially without binding action.

Other objects and advantages of the invention will be apparent during the course of the following description.

In the accompanying drawings forming 35 a part of this specification and in which like numerals are employed to designate like parts throughout the same,

Figure 1 is a plan view of an engine embodying my invention, with the cap of 40 the valve housing removed and the rotary valve removed,

Fig. 2 is a vertical longitudinal section taken on line 2—2 of Fig. 1,

Fig. 3 is a transverse sectional view taken 45 on line 3—3 of Fig. 1, with the valve in place,

Fig. 4 is a front elevational view showing the valve timing,

Fig. 5 is a plan view of the valve housing cap,

Fig. 6 is a perspective view of a rotary valve.

In the drawings, wherein for the purpose of illustration is shown a preferred embodiment of my invention, the numeral 10 designates the cylinders of an internal

combustion engine, which are shown as vertical for the purpose of illustration. A piston 11 is mounted to reciprocate within each cylinder and is connected with a pitman 12, 60 connected with a crank shaft 13.

There may be any suitable number of cylinders, and in the event that there are a plurality of them, the same may be cast in a single block, providing a head 14. Spark 65 plugs 15 are carried by the head and project into the top of the cylinders.

A valve housing is secured to the cylinders or cylinder block and is designated as a whole by the numeral 17. This housing 70 embodies an inner section 18, preferably cast integral with the cylinder block. The numeral 19 designates an outer section or cap, secured to the inner section 18 by bolts 20, carrying nuts 21, with spring washers 75 22 arranged beneath the nuts. The function of these spring washers is to permit of a slight outward movement of the section or cap 19 upon the circumferential expansion of the rotary valve, to be described. 80

The sections 18 and 19 are provided with recesses 23, which are semi-circular in cross section and are in registration to form a cylindrical chamber, having both ends open, and adapted for the reception of a rotary 85 solid valve 24. This rotary solid valve, which may be termed a rotary shaft valve, is provided near one end with an annular flange 25, rotatable within an annular groove 26, formed in the housing sections 18 and 90 19. The function of this flange and groove is to hold the rotary shaft valve against bodily longitudinal displacement, but to permit of the longitudinal expansion of the same, without binding action, as the opposite end of the same is free from connection. The shaft valve is driven by a gear 95 27, preferably secured to its end, near the flange 25, this gear being connected with the crank shaft of the engine to be driven at a 100 suitable speed.

The rotary shaft valve 24 is provided with a plurality of twin units inlet and exhaust ports 28 and 29, there being as many units as there are cylinders, and the units 105 being arranged in proper circumferential adjustment upon the shaft valve, to cause the cylinders to function in proper order. In connection with each unit, it will be seen that the ports are cut close into the center of the shaft valve. Each port is cut to take up one fourth of the circumferential space 110

of the shaft valve, the inlet port 28 taking up one fourth of the circumferential space, and the exhaust port 29 taking up one fourth of the same. The inlet port starts at 5 the end line of the exhaust port, thereby leaving two fourths of the circumferential space of the shaft valve solid, which solid space serves to close the passages to the cylinder, during the two stages of compression 10 and explosion. It is thus seen that I have provided a twin unit inlet and exhaust ports arranged at 90° , and occupying two fourths of the circumferential area of the shaft valve, the remaining two fourths being 15 solid, with the result that upon a complete rotation of the shaft valve the four functions of the engine, to wit, intake, compression, firing, and exhaust will be performed.

20 Each cylinder 10 has a relatively wide common port 30, leading into the upper end thereof, and adapted to be placed alternately into communication with supply and exhaust ports or passages 31 and 32, formed 25 in the housing section 18. The inlet port 28 is adapted to establish communication between the ports 30 and 31, while the exhaust port 29 may establish communication between ports 30 and 32. The charge is fed 30 to the intake port 31 by any suitable means.

I provide gravity operated means to supply oil or other lubricant to the rotatable shaft valve, comprising a suitable number of spaced oil supply pipes 33, which extend 35 through vertical openings in the top of the section or cap 19, and deposit oil upon the periphery of the shaft valve. The construction of the shaft valve is such that it permanently retains the pressure within the cylinders from 40 the flow of oil, which enables the use of the gravity feed which effects a continuous flow

of oil upon the top of the shaft valve. I omit any device to remove the spent oil from the shaft valve, as the sharp edges of the ports 28 and 29 will pick up the refuse oil 45 so that the same is next drawn into the cylinders, upon the intake strokes of the pistons, furnishing lubrication to the cylinder walls and pistons, and after the explosion in the cylinders, the burnt oil is exhausted 50 into the atmosphere.

In view of the foregoing description it is thought that the construction and operation of my engine should be fully understood, it being understood that certain changes in 55 the shape, size, and arrangement of parts, may be resorted to without departing from the spirit of my invention, or the scope of the subjoined claim.

Having thus described my invention, I 60 claim:—

In an internal combustion engine of the character described, a plurality of cylinders, pistons arranged therein, a housing secured to the cylinders and having twin units of 65 inlet and exhaust ports, said housing embodying a cap and having an interior annular groove, yielding means to hold the cap in place, a rotary shaft valve arranged within the housing and having an annular flange 70 rigidly secured thereto and operating within the annular groove, said shaft valve having twin units of inlet and exhaust ports to 75 coat with the first named ports, the inlet and exhaust ports in each twin unit of the shaft valve having their inner ends in the same line, each of such ports occupying substantially one fourth of the substantial space of the shaft valve, and means to rotate the shaft valve.

CHAS. LLOYD MACVEY.
